Primary Examiner—Brian N Vinson*(74) Attorney, Agent, or Firm*—Oblon, Spivak, McClelland, Maier & Neustadt, L.L.P.(57) **CLAIM**

The ornamental design for a gravity fed dispenser or the like, as shown and described.

DESCRIPTION

FIG. 1 is a front elevational view of a gravity fed dispenser or the like, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top, front, and right side perspective view thereof.

The broken-line disclosure in the views is understood to illustrate portions of the article in which the claimed design is embodied, but which form no part of the claimed design, and the irregular broken-line between claimed and unclaimed surfaces is understood to represent and unclaimed boundary between claimed and unclaimed surfaces.
